FIG.1.

FIG.2.

FIG.5.

FIG.3.

FIG.4.

INVENTOR.

HARRY KENIGSON

BY

Carl Miller

ATTORNEY,

the tray 11, as shown in dotted lines in Fig. 3 of the drawing.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A tray set comprising a bottom tray having means to receive eggs, a pair of upright rods fixed to the rear corners of the bottom tray, and formed with longitudinal slots, a pair of upright rods fixed to the front corners of the bottom tray, and having shoulders at the upper ends

thereof, a top tray provided with pivot pins received within said slots, and having means to engage said shoulders, said slots having offset portions at their upper ends to support said pivot pins, said top tray adapted to be swung below the bottom tray in nested relation.

2. An egg tray set comprising a bottom rectangular tray having spaced egg-receiving recesses, a vertical rod fixed to each of the corners of the tray constituting a pair of front rods and a pair of rear rods, each of said front rods having a shoulder at its upper end and each of said rear rods having a vertical slot coextensive with its length each terminating in an offset slot, a top tray having pivot pins movable within said slots and apertures receiving said front rods to support said top tray on said front rod shoulders, said top tray adapted to be swung below the bottom tray into nested relation.

HARRY KENIGSSON.
